(57) CLAIM

The ornamental design for a cosmetic product case, as shown and described.

DESCRIPTION

FIG. 1 is a bottom perspective view of a design for a cosmetic product case;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof;

FIG. 9 is a front exploded view thereof showing a cap thereof removed from a base thereof, with an unclaimed cosmetic product in the form of mascara, which is shown by way of example; and,

FIG. 10 is a bottom perspective exploded view thereof showing the cap removed from the base, with an unclaimed cosmetic product in the form of mascara, which is shown by way of example.

The broken line disclosure of the mascara case in FIGS. 9-10 illustrates the environment of the cosmetic product case and forms no part of the claimed design. The remaining broken lines illustrate portions of the cosmetic product case and form no part of the claimed design.
